UNITED STATES PATENT OFFICE.

FRANK E. HOUSH, OF WINTHROP, MASSACHUSETTS.

DISK-HOLDER.

1,098,154.

Specification of Letters Patent. Patented May 26, 1914.

Application filed February 19, 1914. Serial No. 819,620.

To all whom it may concern:

Be it known that I, FRANK E. Housh, a citizen of the United States, residing at Winthrop, in the county of Suffolk and 5 State of Massachusetts, have invented new and useful Improvements in Disk-Holders, of which the following is a specification.

This invention relates to improvements in disk-holders.

More particularly it relates to improvements in means for conveniently storing, preferably in album or book form, disks containing records for mechanical reproduction of sound. Efforts have heretofore 10 been made in this direction, one of the most successful types being represented by an album in which each leaf is of stout paper and has a pocket opening at the edge of the leaf, large enough to receive a single record. It 15 is found in practice, however, that holders of this type, break at about the middle of one edge, where the weight is concentrated, or where the stress comes between the disk and the paper when the leaf is lifted by its 20 edge to turn it over. No means has hitherto been known, so far as I am aware, to make the paper endure the stress of repeated turning of the leaves, the weight of the disk record being so great, as compared with the 25 weight and strength of the paper which confines it. Hence it has not hitherto been possible to produce albums of this sort that will prove satisfactory in service, and it has been necessary to have cabinets of wood, and 30 other relatively elaborate and expensive constructions of board, or of cloth; or to resort to other devices in which the casing holding one disk is not attached to the casing holding another, but each casing is independent 35 of its neighbors.

It is an object of the invention to overcome the difficulty mentioned in such manner that record disks may be durably contained in a case having the convenience of 40 handling, indexing, and filing possessed by sheets in a book or album, either tight bound or loose leaf; and having strength and durability that are equivalent to the strength and durability of wood for all practical purposes; together with the lightness of weight, the thinness, and the economy of paper. This object can be attained in a manner 45 hereinafter set forth which appears to be absolutely satisfactory in the respects mentioned, so far as my experiments have gone, and which incidentally has other advan-

tages, such as greater safety in protecting fragile disks from breakage by shock.

There are several elements which contribute to the making of a perfect filing case 60 of the sort described. One feature is the provision of a circular line of bearing or support, substantially conforming to the curvature of the edge of the disk, whereby the weight of the disk, and the tension exerted on the paper, is distributed over a long line instead of being concentrated at a single point of tangency. Another is the means of 65 making this line of support, viz., by stitches, as compared with other possible ways such as gluing or riveting, because the stitches interpose a multiplicity of small positive barriers, viz., those parts of the stitches which run transversely through the paper, so that the stress is resisted by the tensile 70 strength of cord, which is superior to that of paper, and is received by the paper in a multiplicity of points, each of which sustains only a greatly sub-divided portion of the 75 entire stress, and, perhaps still more important, the device by which even these points are very largely relieved of shearing stress, so far as the paper is concerned, by the conversion of the stress imposed by the disk on the paper into a bending stress. Another is 80 the shape and closure of the casing by the formation of a restricted throat bearing a certain relation to the diameter of the disk. Another feature is the friction by which the 85 disk is gripped and held with cushion effect; 90 and still another is the means by which the disk is kept seated against the circular barrier, and locked in that position, consisting of a flap at the outer edge of the case, projecting from the back and capable of being 95 turned over on the face, so as to prevent the disk from slipping out, and which is locked by the simple process of closing the album with these flaps folded inward, the stiffness 100 of the paper being such that the disk cannot slip out nor be removed until the leaves of the album have been separated. These and other features will be apparent from a consideration of the construction hereinafter described.

Variations may be made from the precise construction herein illustrated and described without departing from the scope of the patent as defined in the appended claims, the object of which is to cover such features of 105 patentable novelty as exist in the invention disclosed.

One embodiment of the invention is illustrated in the accompanying drawings, in which,

Figure 1 is a side view of a single casing, 5 arranged to be used as a leaf in a loose leaf book; Fig. 2 is an edge elevation of a loose leaf binder containing a number of leaves like Fig. 1, one of which is shown in section on its medial line; Fig. 3 is an edge elevation 10 of a detail, enlarged; and Figs. 4 and 5 are side views of modifications.

Referring to the drawings, the casings for holding the disks are represented as composed of two sheets of strong stiff paper, 15 marked 12 and 13, somewhat larger than the diameter of the disk 11 which is to be contained. One of them, preferably the rear one 13, projects materially farther than the other (to the right, in the drawing,) 20 so as to form a flap 14 which is capable of being folded over upon the face of the front one 12. Both of them extend to the left in such manner as to have a stub portion adapted to be bound, either permanently or loosely 25 in any suitable manner, in a cover or binding. These two sheets are secured together by a line of stitching, 15, 16, 17, which, starting near the top of the outer vertical edge of the shorter sheet, proceeds toward the 30 stub for a distance equal to somewhat less than half the diameter of the disk, and then proceeds farther inward, and downward, and then outward again by a semi-circular curve, to a point at the bottom, and thence 35 out to the said right hand vertical edge at a point far enough from its beginning at the top to admit the disk. The semi-circular curve 16, when constructed as described, will be on a slightly larger radius than that 40 of the disk which the case is to hold; and the dimensions from the top part 15 to the bottom part 17 of the stitching, and from the extreme depth of the semi-circle near the stub to the edge where the fold 18 occurs, 45 should be slightly larger than the diameter of the disk, to allow for the thickness of the disk when the latter is inserted between the two sheets, and to allow for the gradual spreading of the sheets to make the cushioning friction grip that the sheets have on the 50 disk. The line of stitching serves a multiplicity of functions. It fastens together the two sheets, and is the only fastening that need be provided, so that the two together 55 make a case suitable for receiving a record disk, the whole being comparable to a leaf of an album; it limits the distance which the disk may penetrate when pushed in; it provides a line bearing for the inner edge 60 of the disk, which extends around the whole inner half of the disk, fitting it in curvature; it holds the two sheets of stiff paper close together along a definite line close to the edge of the disk so that when a person 65 takes hold of the outer edge of the disk,

either directly, or by lifting the leaf, the two sheets act as one to resist any tendency of that disk to bend the paper, and the bending effect is thus located in a straight line 70 extending across the entire width of the sheet, near the stub, where bending is normal and is harmless; and the holding of two sheets together in this manner provides a frictional grip on the record disk, and a cushion support, both of which I 75 deem of considerable importance. There are also other functions served by this construction. A double thread style of sewing is preferred, in which the thread is locked at each stitch. But whatever be the style of 80 sewing it is evident that the number of places where the thread goes through the two sheets, make a very large number in total, and constitute a sort of net-work limiting the movement of the disk. Of course 85 they get their support only from the paper, but as each penetration is separated at a distance of several of its own diameters from its neighbors on each side, for example 8 or 10 diameters, according to the length of 90 stitch, there is abundant stock of paper on each side of it. Those portions of the thread which lie on the external surfaces of the two sheets, and parallel to those surfaces, perform an additional function, when 95 taken in connection with the stiffness of the paper, in that they render available for holding the disk firmly all that body of the paper which intervenes between places where the stitches penetrate the paper. This will 100 be understood from a consideration of Fig. 105 3, from which it is clear that any pressure of the disk 11 in the direction of the arrow does not impose stress directly on the thread, but tends to separate the sheets 12 and 13, 110 and, in so doing is opposed by those qualities of stiffness and of elasticity which are inherent in the paper. The two sheets 12, 13, lie parallel to each other, or else 115 slightly divergent on the stub side of the line of stitching; and that portion of the stitch which is marked 10 in Fig. 3 tends to hold them parallel; but the insertion of the disk 11 separates them, and in so doing bends each sheet transversely, the bend being more acute the more deeply the disk 120 is inserted, but never becoming a sharp bend. This does not tend particularly toward shearing the paper, because the tough superficial skin of the paper remains unbroken. 125 In practice the resistance becomes great enough to stop a person pushing the disk, before it has got close enough to the stitch to make a bend sharp enough to be in danger of cracking the paper. As the two sheets 12, 13, are rigidly and positively held together by the successive portions 10 of the stitches, and tend to lie in parallelism, they 130 assume a V-shape when separated by insertion of the disk. The farther the disk is

pressed inward, the greater this resistance becomes, but in character it is always a cushioning resistance, because the disk, practically, never gets so far as to reach a positive barrier, and the elasticity of the paper is intervening between the disk and the ultimate barrier afforded by the line of stitching. This produces a frictional grip on the record which extends around its periphery.

5 These characteristics are to be distinguished from a case that may be imagined where a disk is put into a circular pocket having a square instead of a V-shaped cross section, in which case the disk may abut directly against the transverse barrier; and are to be distinguished from the situation where a disk is placed in an ordinary stiff paper envelop, in which the limit is formed by a fold in the paper. This makes a U-shaped

10 construction in which the natural tendency of the paper is to open instead of to close; and in which it is much easier for the paper to conform itself to the shape of the edge of the disk, and so for the disk to reach a solid bearing against the fold of the paper.

15 In the first of these cases, there would ordinarily be no friction on the sides; in the second there would be so little friction, or so easily disappearing with usage, that the lateral pinching effect of the invention would not be attained. The degree of friction with which any particular disk will be thus held depends upon the relation between the thickness and diameter of the

20 disk and the diameter of the circular stitching. It is an advantageous characteristic of the invention that the construction illustrated works satisfactorily upon disks varying both in thickness and in diameter. In

25 practice, record disks for reproduction of sound are made in standard sizes, as "10-inch", or "12-inch", and the leaves of an album for the envelops would in practice be designed for the particular size; but the

30 disks which are nominally of the same size do in fact vary somewhat from that precise size. If the diameter of stitching be, for example, $10\frac{1}{2}$ inches, it will accommodate a disk of ten inches of any of the thicknesses

35 now common on the market, holding it frictionally, and will also accommodate and hold frictionally a "10-inch" disk which really measures, for example, only $9\frac{1}{2}$ inches.

40 I regard it as important that my casing will hold, with gentle frictional cushion-grasp, disks of such different sizes. Another feature of importance is a supplementary means of maintaining the disks within the casing. Hitherto it has usually been thought

45 necessary, where disk holders have been assembled in book form, to have the pockets open at the top, so that the disks would not fall out during handling. This involves the disadvantage that, in order to extract

50 a single disk, it is usually necessary to open the book rather widely in order to relieve that portion of the disk which is next the binding from pressure while being drawn out, and, more important, the action of withdrawing or of inserting the disk tends to

55 wrench or tear the leaf from its binding. In my invention, the frictional hold upon the disk within may be so strong that the pockets may open at the edge of the casing or leaf which is remote from the binding, so that the direction of pressure or pull, when putting the disk in or out, is squarely toward or from the binding edge. These principles hold true when the under line of stitching is carried straight out from the

60 bottom of the portion 16, as it might be, on the line 17' as indicated in Fig. 4; but I have devised a further improvement, which is represented by the location in which the stitching 17 in Fig. 1 is shown, in which a

65 narrowed or frictional throat entrance is formed. To do this the circular line of stitching 16 is continued a little past the bottom of the circle and upward to the right, as seen in Fig. 1, to 17'' where the

70 line 17 begins. A similar construction may be employed at the top, at the junction 15'', between the lines 15 and 16. Whether one or both of these variations from the possible parallel entrance borders 15', 17', be

75 practised, a throat is formed whose narrowest part is represented by the distance between the points 15'' and 17'', or between either and the opposite line. These points must obviously be far enough apart to admit the largest record of the nominal size for which the casing is to be used, but, with that limitation, they may be materially nearer together than are the broadest parts of the

80 space where the record ultimately rests, and when so constructed they serve the purpose of making the exit of the record within somewhat difficult. The frictional pressure on a disk in passing these, being only temporary, may be greater than would be desirable for the disk to impose permanently

85 on the paper, as upon the line 16, adjacent to which the disk remains for a long period of time. It may in fact be so great as to prevent the disk from falling out by gravity, or during ordinary handling and turning of leaves, notwithstanding the leaf be held and even shaken or jarred with the mouth of its pocket downward.

90 The flap 14 is provided by folding one of the sheets, preferably the rear sheet, on a line 18 close to the mouth of the pocket, over upon the face of the other sheet. The mouth of the pocket thus closed is so located that the fold thus made is near to the edge of a

95 disk contained in the pocket, as illustrated. This furnishes an additional means of holding the disk in; and also makes sure that all disks in the album are properly seated in their pockets when the album is closed, be-

100 105 110 115 120 125 130

cause if any disk be not so, its flap 14 cannot be closed, thus calling attention to the fact that the disks need adjustment; and it serves the further function of locking the disks in place, because, as illustrated in Fig. 2, when the album is closed, each flap 14 is held down flat by being pinched within the stack of leaves.

The hole 22 may be cut through the center 10 of both sheets, thus exposing the label on the disk within. Near the stub portion of the leaf, lines or creases 23 may be formed as is customary with loose leaf books, to facilitate bending; and in the stub itself, a filler or 15 guard 21 may be employed for the sake of strength, if the leaves are to be used as in a loose leaf book. Such a guard, as illustrated, is a simple piece of card board glued between the two leaves, but this may be 20 omitted, particularly in books having permanent binding.

As the invention may be used with any kind of a loose leaf or permanent binding, the style of loose leaf binding represented in 25 Fig. 2 is to be understood as merely indicating one style of such binding with which the leaves may be used, in which the holes 19 in the stub of the sheet are penetrated by a binding post 19' and held by covers and a 30 thumb nut 19".

The invention will also be found useful for holding individual record disks apart from albums, affording a greater protection to the disk by its cushion grasp and by its 35 line support, as distinguished from the tangential and solid bearing which disks have on the edges of the square envelops at present so commonly in use. For this the form of stitching shown in Fig. 1 may be used, or 40 other forms. Simple forms are illustrated in Figs. 4 and 5. The former represents two square sheets 12', 13', sewn together by stitching on the line 15', 16, 17', the lines 15' and 17' being parallel to each other and 45 the line 16 being a semi-circle connecting them. Fig. 5 shows similarly two square sheets 12', 13', but the line of stitching at the top marked 15''' is horizontal over the center of the pocket, and runs only a short 50 distance; the stitching 16''' is oblique and straight at the lower inner quadrant of the disk, limiting its depth of insertion and at the same time supporting it; and the line of stitching 17''' is oblique, sloping upward 55 and outward, and also forming a support. Additional fastening means, such as glue, may be provided if needed, to hold the two sheets securely together; and this may be put anywhere except in the region used for 60 the pocket and entrance thereto. When such a casing as is illustrated in Fig. 5 is used, the casings filled with disks may be stored on edge, and the edge which is the top may bear an index number, filing mark, or blank 65 for notes regarding contents of the casing,

any of which is typified by the index numeral 43 portrayed in the upper right hand corner. Such a mark furnishes a natural guide to indicate which is the top and which is the bottom edge, so that the person using it will naturally put downward the edge with the lines 16''' and 17''', thus utilizing the force of gravity in addition to that of friction for holding the disk in the casing, while permitting the convenience of a file in which each record stands on edge and is therefore accessible and removable without disturbing others. In this case it will be noted that although the lines of stitching are straight instead of curved, they embody the 80 function of certain parts of the invention in that they afford a frictional V-grip on those parts of the disk which are next to them, so that when the casing is filed on edge the weight of the disk is suspended from various parts of the sheets 12', 13', and is not concentrated at the bottom. If the line 16''' were a vertical line, in a casing formed as a leaf of a book, there would be danger of the leaf bending and after a time breaking on 90 that line. Consequently when the casings are to be made up as leaves of a book it is always desirable that the line of stitching which is toward the binding be either curved or oblique as I have found in practice that 9 such construction prevents the bend in the paper from occurring on the line of the stitching.

I claim as my invention:

1. A holder for a disk comprising the 100 combination of two sheets of relatively stiff, elastic material and means fastening them closer together than the thickness of the disk, there being an opening for entrance of a disk between the sheets; said fastening 105 running on a curve for a part of its length, adapted to follow the contour of an inserted disk.

2. A holder for a disk comprising the 110 combination of two sheets of paper fastened together in close proximity to each other along a curve, there being an opening between the sheets for admission of the disk; whereby the insertion of the disk through 115 said opening spreads the sheets elastically in V-shape from said fastening, thereby holding the edge of the disk frictionally.

3. A holder for a disk comprising the 120 combination of two sheets of paper stitched together to form a pocket open at one edge, the line of stitching passing inward from 125 said open edge, around a curve, and outward, and the paper sheets being held close enough together by said stitching, so that a disk separates them when inserted and is held frictionally around a considerable portion of its edge.

4. A holder for a disk comprising the 130 combination of two sheets of paper stitched together to form a pocket open at one edge,

- the line of stitching passing inward from said open edge, around a curve, and outward, and the paper sheets being held close enough together by said stitching, so that 5 a disk separates them when inserted and is held frictionally around a considerable portion of its edge, the inward and outward lines of stitching forming a contracting throat through which the disks must pass, 10 narrower than the portion of the pocket where the disk normally rests.
5. A protective holder for a disk, comprising two sheets fastened together, forming a pocket for the disk between them; said fastening being on a curved line, conforming 15 to the edge of the disk and holding the sheets closer together than the thickness of a disk, whereby the sheets resist elastically the insertion of the disk and hold it frictionally away from said fastening when 20 inserted.
6. A protective holder for a disk, comprising a leaf adapted to be bound in an album, and comprising two sheets fastened together, 25 forming a pocket for the disk between them; said fastening being on a curved line, conforming to the edge of the disk and holding the sheets closer together than the thickness of a disk, whereby the sheets resist elastically 30 the insertion of the disk and hold it frictionally away from said fastening when inserted, there being a space between said curved fastening and the binding for flexure of the leaf.
- 35 7. The combination of a multiplicity of holders for disks, each holder comprising two sheets of paper fastened close together along a curved line, there being an opening between the sheets for insertion of a disk; 40 one of each such pair of sheets having a flap adapted to fold over said opening and lie upon the other sheet; and means for binding the said multiplicity of holders together in a book, whereby when the book is closed, 45 said flaps are held folded over said openings by the book closure.
8. The combination of a multiplicity of holders for disks, each holder comprising two sheets of paper fastened close together 50 along a curved line, there being an opening between the sheets for insertion of a disk; one of each such pair of sheets having a flap adapted to fold over said opening and lie
- upon the other sheet; means for binding said multiplicity of holders together on a 55 straight line opposite said opening.
9. The combination of a multiplicity of holders for disks, each holder comprising two sheets of paper fastened close together along a curved line, there being an opening 60 between the sheets for insertion of a disk; one of each such pair of sheets having a flap adapted to fold over said opening and lie upon the other sheet; means for binding said multiplicity of holders together on a 65 straight line at a little distance from the curvilinear fastening, the intervening material being flexible.
10. A holder for a multiplicity of disks comprising sheets of paper bound together 70 in pairs in the form of a book, each pair of sheets having a line of stitching fastening the sheets together and forming a pocket; said pocket being open for insertion of a disk at the edge remote from, and parallel 75 to, the binding, and said stitching extending from said edge inward toward said binding, and then farther inward, downward and outward around a semi-circular line, and then outward to said edge remote 80 from the binding; combined with means for holding disks in the pockets thus formed.
11. The combination of a multiplicity of holders for disks, each holder comprising two sheets of paper fastened close together 85 along lines constituting a pocket adapted to hold a disk, there being an opening between the sheets for insertion of the disk; and means for binding said holders together; the line of fastening which is toward the 90 binding being not parallel thereto.
12. A holder for a disk comprising the combination of two sheets of relatively stiff, elastic material and means fastening them together closer than the thickness of the 95 disk, along lines; there being an opening for entrance of a disk between the sheets; said lines being located so as to form a pocket for the disk, limiting its movement between the sheets elastically.
- Signed by me at Boston, Mass., this tenth day of February, 1914.
